STUD BOX

William H. St. Thomas, Gloversville, N. Y., assignor to St. Thomas Inc., Gloversville, N. Y., a corporation of
New York

Application May 2, 1955, Serial No. 35,770

Term of patent 14 years

(Cl. D58—12.6)

FIG. 1.

FIG. 2.

FIG. 3.

FIG. 4.

Fig. 1 is a perspective view of a stud box embodying my new design shown in closed position;

Fig. 2 is an end elevational view thereof;

Fig. 3 is a perspective view thereof, shown in open position; and

Fig. 4 is a perspective view thereof shown in disassembled position.

The dominant feature of my design resides in the appearance presented by the interior of the box, as shown in Figs. 3 and 4.

I claim:

The ornamental design for a stud box, substantially as shown and described.
